UNITED STATES PATENT OFFICE.

CLARK FREE RIGBY, OF FOXBURG, PENNSYLVANIA, ASSIGNOR OF THREE-EIGHTHS TO LEWIS WATSON RAISON, WILLIAM ALEXANDER STOFER, AND JOHN M. HARPER, ALL OF SAME PLACE.

STEAM-VALVE.

SPECIFICATION forming part of Letters Patent No. 366,028, dated July 5, 1887.

Application filed March 24, 1887. Serial No. 232,247. (No model.)

To all whom it may concern:

Be it known that I, CLARK FREE RIGBY, of Foxburg, in the county of Clarion and State of Pennsylvania, have invented certain new and useful Improvements in Steam-Valves; and I do hereby declare the following to be a full, clear, and exact description of the invention, such as will enable others skilled in the art to which it pertains to make and use it, reference being had to the accompanying drawings, which form part of this specification.

My invention relates to an improvement in steam-valves; and it consists in the combination of the valve-chest, which is made tubular in shape and provided with inlet and exhaust ports, with the valve, which is formed of two shells which are placed one inside of the other and provided with corresponding inlet and exhaust ports, the concave heads which are placed inside of the valves, and suitable packing-rings, as will be more fully described hereinafter.

Figures 1 and 2 are vertical sections of the cylinder and valve embodying my invention, 25 the valve being shown in different positions. Fig. 3 is a side elevation of the valve alone.

A represents the valve-chest, which is made tubular in shape, and which is closed at both its ends, and provided with two ports through 30 its side for the free admission of the steam to the ends of the valve. Through this chest are made the inlet ports C and the exhaust-port D. In the inner surface of this chest, and extending entirely around, are made grooves which correspond to the ports C D, so that the steam can pass entirely around the valve and enter freely at all of its ports.

The valve E is formed of two concentric split rings, G H, which are provided with inlet and exhaust ports to correspond to the ports in the chest, and in each end of the two shells is placed a concaved head, I, which extends inward beyond the inlet-port C. These heads are provided with openings or ports J, 45 which extend to the inlet-ports C, so that when the live steam enters either one of the ends of the chest it will pass into one of the heads I through the ports J C. These heads I serve to separate the live from the exhaust steam, and

in order to form a perfectly-tight joint between the head and the inner shell, H, suitable packing-rings, L, are used. The two heads are connected together by the valve-rod N, by means of which the valve is moved back and forth in the chest. The ends of the heads I bear against the valve extensions or supports O, formed upon the ends of the two shells G H, as shown. In the outer surface of each head there is cut a groove, which is to be filled with soft metal, which forms a seat for the packing-rings. 60 When the valve is being repaired, this seat can be readily removed and a new one inserted.

In order to prevent a leakage between the edges of the outer shell, G, suitable recesses are made in its edges, and in these recesses are placed small plates Q, which extend across the opening between the edges of the shell, and thus prevent any passage of steam back and forth between the inlet and exhaust ports. When the valve is moved endwise into one 70 position, the inlet-ports are closed and the exhaust-port is opened, and when the valve is moved endwise in the opposite direction the exhaust-port is closed and the inlet-ports are opened. The extensions O upon the valvesupport the center and the ends of the valve and never travel past or over the steam-ports.

The two shells G H are used, so that when the valve becomes worn the outer shell, G, can be removed and replaced by another, and thus 80 a practically new valve is made, for none of the interior parts have to be removed, nor do they have any wear, as they have no movement of their own. The outer shell, G, is turned larger than the bore of the steam-chest and 85 split lengthwise, so that it can be forced together small enough to enter the steam-chest, then adjust itself to its seat.

A valve constructed as above described is self-adjusting and a perfect balance, and can 90 be repaired at a very small cost, for the reason that the wear comes only upon the outside shell, G. When the steam-chest has been bored so often that it becomes too large, a bushing can be placed inside of it, so as to fit the valve. 95

Having thus described my invention, I claim—

1. The combination of the two shells G H,

provided with the extensions O upon their ends and having the exhaust ports and passages, with the concaved heads which are placed inside of the shells, substantially as shown.

2. The combination of the two shells G H with the concaved heads I, placed therein and provided with suitable packing-rings, and the groove which is filled with soft metal, substantially as described.

3. The combination of the two split shells

G H, provided with inlet and exhaust ports, with the concaved heads I, also provided with inlet-ports and suitable packing-rings, and the plates Q, which are inserted in the edges of 15 the outside shell, substantially as set forth.

In testimony whereof I affix my signature in presence of two witnesses.

CLARK FREE RIGBY.
